UNITED STATES PATENT OFFICE.

HORACE L. KINGSLEY, OF RACINE, WISCONSIN.

ROAD-CART.

SPECIFICATION forming part of Letters Patent No. 284,132, dated August 28, 1883.

Application filed August 1, 1883. (No model.)

To all whom it may concern:

Be it known that I, HORACE L. KINGSLEY, of Racine, in the county of Racine and State of Wisconsin, have invented certain new and useful Improvements in Road-Carts; and I do hereby declare the following to be a full, clear, and exact description of the invention, such as will enable others skilled in the art to which it pertains to make and use it, reference being had to the accompanying drawings, which form part of this specification.

My invention relates to an improvement in road-carts; and it consists—

First, in the combination of pivoted shafts provided with a cross-piece, an arm which extends outward from the axle, and a set-screw which passes through both the cross-bar of the axle and the front end either of the arm which extends out from the axle or the swinging nut which is attached thereto, for the purpose of raising and lowering the shafts to correspond to the height of the horse. The object of this part of my invention is to adjust the shafts, and through the shafts the proper position of the body, so as to correspond to the height of the horse, and thus prevent the body from tilting either too far forward or backward.

Second, in the combination of the axle, the side springs which are attached thereto, and which have their front ends formed into scrolls, the ends of the scrolls being attached to the body either by means of equalizers or by means of cross-bars which extend across the under side of the body, as may be preferred. The object of this part of my invention is to so construct the front ends of the springs and attach them to the body that they will automatically lengthen or shorten, according to the weight which is placed in the body.

Figure 1 is a side elevation of a cart embodying my invention, shown partly in section. Fig. 2 is a detail view, showing the arm which extends outward from the axle. Fig. 3 is a detail view of the swing-link.

A represents the axle, and B the body. This body may be given any shape or form that may be preferred, but is here shown as cut away at the front corners, so as to enable the person to step into the vehicle from the front of the wheels. I do not limit myself in any respect so far as the mere construction of the

body is concerned, for it may be made to enter either from the rear or front end, as may be preferred. The springs C are secured to the axle in the usual manner, and extend forward 55 as far as the rear end of the body, to which they may be attached either by means of equalizers or any other devices that may be preferred for that purpose. The front ends of these springs project forward a suitable distance, and are bent into the scrolls D, as shown. The ends of these scrolls will be attached to the body either by equalizers or to the ends of the cross-bar which extends across under the body, as may be preferred. The front ends of 65 the springs being curved, as here shown, they automatically lengthen or shorten, according to the weight which is placed in the body, causing the body to ride more easily, preventing the horse motion from being imparted to 70 the body, and cheapening the cost of construction by dispensing with the usual connecting parts. The scrolls of the springs are placed under the front end of the body because the lightest part of the weight comes upon this 75 end. As the largest portion of the weight comes upon the rear end of the body the heaviest and strongest portion of the spring should come under this end, so as to support it. Should the scroll be placed under the rear 80 end of the body, the body would have a constant tendency to tilt backward.

In order to regulate the height of the shafts so as to correspond to the height of the horse, and to regulate the position of the body 85 so that it will not tilt too far forward or backward, a cross-bar, E, is secured between the rear ends of the shafts at any suitable distance in front of the axle. These shafts are pivoted upon either the top or front side of the axle, 90 so as to have a free adjustment, according to the size of the horse which is hitched to the vehicle. Secured to the center of the axle, and extending outward from its under side, is an arm or rod, G, to the front end of which is 95 preferably attached a swinging nut or loop, I. Passing down through the cross-bar and entering the swinging loop upon the front end of this rod or arm is a swiveled set-screw, J. The arm being rigidly secured to the under side of the axle and the shafts being hinged thereto, by 100 turning this set-screw the shafts may be forced

either upward and away from the rod or arm or may be drawn down toward it, as may be desired. In case a large horse is hitched to the vehicle, and the shafts were not properly adjusted beforehand, the body would be tilted too far backward, and thus made unpleasant to ride in. To overcome this defect the shafts must be raised by turning the set-screw so as to correspond to the height of the horse. If 10 a smaller horse is hitched to the vehicle, it is necessary to lower the shafts correspondingly. Although one rod is here shown as projecting out from the axle, and only one set-screw is shown, there may be two of the rods or arms 15 and two set-screws, one rod and set-screw upon each side of the vehicle. In order to turn this screw and adjust the shafts without leaving the vehicle, a hole is made through its bottom, and through this bottom can be inserted a 20 socket-wrench, which will be long enough to reach down and catch over the head of the screw. This construction enables the rider to adjust the inclination of the body to suit himself. A swinging nut or loop is used upon the 25 front end of the rod or arm for the purpose of allowing the screw to be freely moved without binding. As the front end of the body is raised or lowered more or less upon a circle, it becomes necessary to allow some play for the

screw, and a swinging nut or loop is used for 30 that purpose.

I am aware there are various ways of adjusting the shafts to different heights, so as to keep the body horizontal when the vehicle is used with different-sized horses, and I do not 35 claim such, broadly; but the forwardly-projecting bar, with the swing-link and screw, is a simple and effective device, and I wish to limit my claim thereto.

Having thus described my invention, I 40 claim—

1. In a road-cart, the combination of the axle, the springs, the body, the forwardly-projecting bar or arm, the swing-link, the screw, and the pivoted shaft-frame, the parts being 45 arranged to operate substantially as shown.

2. In a road-cart, the combination of the axle, the springs, and the body, the front ends of the springs being formed into scrolls and connected to the body, substantially as set 50 forth.

In testimony whereof I affix my signature in presence of two witnesses.

HORACE L. KINGSLEY.
